United States Patent Office.

HORACE B. MARSHALL, OF WALDOBORO, MAINE, ASSIGNOR TO HIMSELF AND WILLIAM W. LUMMUS, OF LYNN, MASSACHUSETTS.

Letters Patent No. 77,063, dated April 21, 1868.

IMPROVEMENT IN BOOTS AND SHOES.

The Schedule referred to in these Letters Patent and making part of the same.

TO ALL PERSONS TO WHOM THESE PRESENTS SHALL COME:

Be it known that I, HORACE B. MARSHALL, of Waldoboro, in the county of Lincoln, and State of Maine, have invented a new and useful Improvement in Shoes, Bootees, and Gaiter-Boots; and I do hereby declare the same to be fully described in the following specification, and represented in the accompanying drawings, of which—

Figure 1 is a front view, and

Figure 2 a side elevation of a shoe made in accordance with my invention—

Such invention having reference to the closing of the instep-opening of the shoe, and being an improved shoe as made with two interclosing series of loops, and a single lacing or cord going through them, the whole being as hereinafter described.

In the drawings, A is the cloth gaiter, shoe, or boot, of ordinary form and material. There projects from each edge of the instep-opening a series of long or tubular loops, *aa*, which are arranged at equal distances apart, and with spaces, *bb*, of like width between them. The loops of either of such edges are placed directly opposite the spaces between the loops of the other edge, in order that when the two edges are brought into contact, the loops of one may enter and close the spaces between the loops of the other of the said edges. A lacing-cord, *c*, attached to the shoe, and run up through all the loops of both series, serves to close the edges of the opening together, which it will do when drawn tightly.

Generally speaking, these loops are to be formed of pieces of strong leather *BB*, suitable doubled, folded, and cut, and applied to the shoe-opening as a binding or facing is usually affixed to a shoe. Near the upper portions of these pieces, eyelets *dd* may be inserted in the shoe to enable the lacing to be run through them and be fastened by means of them.

This mode of connecting the edges of the instep-opening gives a very neat finish or appearance to the shoe when on the foot of a person, and dispenses with the usual ranges of eyelets let into the shoe. It requires but one lacing-cord. The unlacing of the shoe is quite as easy as by the eyelet-system.

Figure 3 is a cross-section taken through one of the loops, and the space for its reception.

Figure 4 is a view of one of the two series of loops and the lacing as they appear when the shoe is open at the instep-opening.

What I claim as my invention and improvements in boots, bootees, gaiter-boots, and shoes, and desire to secure by Letters Patent, is—

Making or forming loops *aa*, of flexible material, alternately on each side of the openings for the string or lacing.

And, in combination with the loops above claimed, I claim a flexible string or lacing to draw the loops together.

I also claim, in combination with the loops and lacing, one or more eyelet-holes *dd* to facilitate the fastening of the lacing.

I claim making or forming the loops for the string or lacing alternately on the edges of the openings of the various kinds of boots and shoes, by perforating or cutting out the binding or edge-facing of said openings.

HORACE B. MARSHALL.
